UNITED STATES PATENT OFFICE.

ANTONIO CASALE, OF SCRANTON, PENNSYLVANIA.

TRAIN-CONTROL SYSTEM.

1,172,431.

Specification of Letters Patent. Patented Feb. 22, 1916.

Application filed January 22, 1915. Serial No. 3,708.

To all whom it may concern:

Be it known that I, ANTONIO CASALE, a citizen of the United States, residing at Scranton, in the county of Lackawanna and State of Pennsylvania, have invented a new and useful Train-Control System, of which the following is a specification.

The present invention appertains to train control systems, and is particularly an improvement over the train control system disclosed in my co-pending application Serial No. 863,112, filed September 23, 1914.

One object of the invention is the provision of an electrical system, embodying a normally closed train carried circuit having means interposed therein for normally holding an actuating mechanism for the throttle lever and engineer's brake valve in inactive position, means being provided for opening the said circuit when the train enters a dangerous zone, or upon the happening of an accident to the system, or the like, so that the actuating mechanism may be released for throwing the throttle lever and actuating the brake valve to bring the train to a halt.

It is also within the scope of the invention to provide a train control system of the nature indicated, improved generally in the arrangement and combination of the component elements, to enhance the utility of the system and to enable the system to operate properly under the various conditions.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in the accompanying drawings, wherein:

Figure 1 is a diagrammatical view of a portion of the track, illustrating three blocks thereof and depicting a train in one block. Fig. 2 is a fragmental diagrammatical view illustrating a modification. Fig. 3 is an enlarged side elevation of one of the brush devices. Fig. 4 is a view illustrating a modified form of brush device, and illustrating in section, a modified form of sub-rail. Fig. 5 is a side elevation of the modified form of sub-rail.

In carrying out the invention, the rails of the track are insulated at suitable intervals, to provide the blocks, three blocks, designated A, B and C, being illustrated in the drawings, and the traffic rails of the block C being designated 1 and 2.

A partial electrical circuit is associated with each block of the track, only one of the partial track circuits being illustrated in Fig. 1, and this embodies a pair of sub-rails 3 and 4 disposed at the opposite sides of the rails of the block B and adjacent one end of the said block, or that end of the block B adjacent the block A. A similar pair of sub-rails 5 and 6 are disposed at the opposite sides of the rails of the block B at the other end of the block B or adjacent that end of the block B adjacent the block C. The rails 3 and 5 at one side of the block B are connected by an electrical conductor 7 having interposed therein, a suitable resistance 8. The rail 5 is connected by a conductor 9 to the adjacent end of the rail 1 of the block C, and the sub-rails 4 and 6 at the opposite side of the block B are connected by a conductor 10, while the rail 6 is connected to the rail 2 of the block C by a conductor 11. The ends of the rails 1 and 2 of the block C at the remote end of the said block are connected by a suitable resistance 12, whereby the sub-rails 3, 4, 5 and 6, the rails 1 and 2 of the block C and the resistances 8 and 12 are connected in series.

In the drawing, the train T occupying the block B is depicted conventionally and a second train T' is also designated as occupying the block C. The train T carries a pair of brush devices 13 and 14 at opposite sides thereof, and each of the brush devices embodies a shoe 15 which is spring pressed so as to yield when riding upon or encountering one of the sub-rails. The train T carries a partial electrical circuit which cooperates with the partial track circuit to form a complete circuit, under certain conditions, and said train carried circuit comprises a conductor 16 which is terminally secured to the shoes 15 of the terminal brush devices 13 and 14. The conductor 16 has interposed therein in series, the relay electromagnets 17, 18, 19, 20 and 21, the electromagnets 18 and 20, being mounted upon a single core 22 and the electromagnets 17 and 21 being mounted upon a single core 23 also. A battery or other source of electrical current 24 is interposed in the conductor 16. The electro-

magnet 19 has the lowest resistance and is the most sensitive of the said electromagnets, and the electromagnets 18 and 20 have a greater resistance and are less sensitive than the electromagnet 19, while the electromagnets 17 and 21, have greater resistance and are less sensitive than the magnets 18 and 20, in order that the magnets 19, 18—20 and 17—21 may be energized successively to 10 a sufficient operative degree, accordingly as the intensity of the current traversing the electromagnets is increased by the cutting out of the resistances of the partial track circuit. The train T also carries an auxiliary 15 normally closed electrical circuit 25 which includes an armature switch 26 coöperating with the electromagnet 19 and adapted to disengage a contact 27 under the influence of the spring of the armature switch 26. A 20 conductor 28 is connected to the armature switch 26 and to one terminal of a battery or source of current 29 carried by the train, and the other terminal of the battery 29 is connected by a conductor 30 to a solenoid 31. 25 The solenoid 31 is connected by means of a conductor 32 to a second solenoid 33, and the solenoid 33 is connected by a conductor 34 to the contact 27. The armature switch 26 is employed for closing the circuit 25 when 30 the brush devices 13 and 14 are engaged by the sub-rails, and the brush devices 13 and 14 have means for normally connecting the conductors 34 and 28 of the circuit 25 to close the said circuit when the brush devices 35 13 and 14 are released from the sub-rails, as will hereinafter more fully appear.

The solenoid 33 is employed for normally holding an actuating mechanism for a throttle lever actuating device in inoperative or 40 idle position, in order that when the solenoid 33 is deenergized in any manner whatever, the actuating mechanism will be brought into operation for swinging the throttle lever. To this end, a pipe 35 which 45 connects the air or pressure fluid reservoir 36 and a cylinder 37, is provided with a controlling valve 42. The piston 38 which is slidable within the cylinder 37 has its piston rod 39 engaged operatively to the throttle lever 40 whereby the admission of air into the cylinder 37 will swing the throttle lever partially back, and the throttle rod 41 will then partially shut off the admission of steam into the engine cylinders. The valve 55 42 is provided with an operating arm 43 which is connected to the core 44 of the solenoid 33 by means of a link 45, a spring 46' being connected to the arm 43 and the link 45, whereby when the solenoid is deenergized, the spring 46' will swing the valve arm 43. The valve 42 is normally closed, since the solenoid 33 being energized will attract the core 44 and will swing the valve arm 43 to such a position as to hold 60 65 the valve 42 closed, and whereby the passage

through the pipe 35 is closed. The actuating device 37—38—39 for the throttle lever will thus be idle under normal conditions.

The solenoid 31 is employed for normally holding in inoperative position, an actuating mechanism which is connected operatively with the throttle lever and engineer's brake valve, whereby upon the deenergization of the solenoid 31, the throttle lever will first be swung to shut off the passage of 75 steam into the engine cylinders, and in which event the brake valve will be operated to set the air brakes of the train. To this end, a pipe 46 connects the air reservoir 36 and a cylinder 47 whose piston 48 has its piston rod 49 arranged to coöperate with the throttle lever for swinging the same backward. The pipe 46 is connected to one end of the cylinder 47, and a pipe 50 is connected to the other end portion of the cylinder 47 and is 80 in turn connected to a cylinder 51 having a piston 52 working therein, the piston rod 53 of the piston 52 being operatively connected to the brake valve 54 which when actuated by the movement of the piston 52 85 enables the air to set the air brakes. The pipe 46 has a controlling valve 55 therein and the valve has an actuating arm 56 which is connected to the core 57 of the solenoid 31 by means of a link 58, a spring 59 being connected to the arm 57 and link 58. The valve 55 is normally closed due to the attraction of the core 57 by the solenoid 31 and when the solenoid is deenergized, the spring 59 will swing the valve 55 open, to admit the 90 air into the cylinder 47 and then into the 95 cylinder 51.

The device for normally closing the circuit 25 embodies a conductor 60 connected to the conductor 34 of the circuit 25 and to a 105 contact 61 with which a switch lever 62 is coöperable. The switch lever 62 is carried by the switch 14 and is operatively connected with the yieldable or movable shoe 15 of the brush device 14 by means of a link 63. 110 A conductor 64 connects the conductor 28 of the circuit 25 with a contact 65 with which a switch lever 66 is coöperable, the switch lever 66 being carried by the brush device 13 and being operatively connected with the 115 shoe or contact member 15 of the brush device 13 by means of a link 67. The switch levers 62 and 66 are connected by a conductor 68 and the switch levers 62 and 66 are normally in engagement with the contacts 120 61 and 65 respectively. When the shoes 15 of the brush devices 13 and 14 are released, the brush devices 13 and 14 being disengaged from the sub-rails will open the circuit through the conductor 16—whereby the 125 electromagnet 19 will be deenergized, so that the armature switch 26 will be retracted by its spring out of engagement with the contact 27. Thus, two devices are employed 130 for closing and opening the circuit 25, and

they are connected in parallel to one another.

A device controlled by the electromagnets 18 and 20 is employed for connecting the conductors 28 and 32 of the circuit 25 to shunt off the solenoid 33 whereby the said solenoid will be deenergized and to this end an armature switch 69 co-operates with the core 22 of the magnets 18 and 20, and is 10 spring pressed so as to be normally spaced from the contact 70 with which it co-operates. The armature switch 69 is connected by means of a conductor 71 to the conductor 32, and the contact 70 is connected by a conductor 72 to the conductor 28. Thus, when the magnets 18 and 20 are energized; the armature switch 69 will be attracted, and will engage the contact 70, whereby the conductors 71-72 and switch 69 will form a 15 shunt connecting the conductor 32, between the solenoids 31 and 33, and the conductor 28 which is connected to the battery 29, and as a consequence, the current from the battery 29 will not traverse the solenoids 33, 20 due to the short circuit established by the closing of the circuit through the conductors 71 and 72.

A device is employed in connection with the magnets 17 and 21 for establishing a 30 shunt bridging the conductors 30 and 64, for cutting out the solenoid 31, as well as the solenoid 33, whereby both of the solenoids will be deenergized. Thus, an armature switch 73 co-operates with the core 23 35 of the magnets 17 and 21 and is spring pressed so as to normally be disengaged from a contact 74 with which the switch 73 co-operates. The switch 73 and contact 74 are connected by conductors 75 and 76, respectively, to the conductors 30 and 64.

The brush device 13 is illustrated in detail in Fig. 3, it being understood that the brush devices 13 and 14 are duplicates of one another. The brush device 13 embodies 45 the shoe or contact 15 adapted to ride upon the sub-rails and having upstanding guide rods 78 slidably through the frame 79 which is attached to the truck or other part of one car or coach of the train. Springs 80 are 50 disposed between the shoe 15 and frame 79 around the rods 78 to yieldably depress the shoe. The switch lever 66 carries a contact member 66^a co-operable with the contact 65 which is carried by the frame 79, whereby 55 the shoe 15 being depressed under the influence of the springs 80, will normally hold the contact member 66^a of the switch lever 66 in engagement with the contact 65. This is true of both of the brush devices 13 60 and 14.

In operation, supposing the blocks B and C to be clear, and assuming that the train T is approaching and entering the block B from the block A, the partial track and 65 train carried circuits will be open until the

brush devices 13 and 14 encounter the sub-rails 3 and 4. Thus, the shoes 15 of the brush devices 13 and 14 being normally depressed, will cause the switch levers 62 and 66 to be swung into engagement with the 70 respective contacts 61 and 65. This will close the circuit 25 under normal conditions, or when the brush devices 13 and 14 are released from the sub-rails. As a consequence, the current from the battery 29 75 will traverse the conductor 30, the solenoid 31, conductor 32, the solenoid 33, the conductor 34, the conductor 60, the switch lever 62, the conductor 68, the switch lever 66 and the conductor 64. The solenoids 31 80 and 33 will therefore be normally energized, to hold the valves 42 and 55 closed. The brush devices 13 and 14 being disengaged from the sub-rails, will open the circuit through the conductor 16, and as a result, the magnets 17, 18, 19, 20 and 21 will be deenergized, and the armature switches 26, 69 and 73 will normally be open. Now, as the train T passes the sub-rails 3 and 4, assuming the block C to be clear, the brush devices 13 and 14 in contacting with the sub-rails 3 and 4 will close the circuit through the co-operating partial circuits of the train and track. Thus, the current from the battery 24 will traverse the conductor 16 and 95 its electromagnets, the rail 3, the conductor 7 having the resistance 8 therein, the rail 5, the rail 1, the resistance 12, the rail 2, the conductor 11, the rail 6, the conductor 10, and rail 4. The resistances 8 and 12 being interposed in the said circuit, will so weaken the current, that only the most sensitive magnet 19 will be sufficiently energized so as to attract its armature switch. Consequently, the armature switches 69 and 100 105 73 will remain open, while the switch 26 will be closed, to close the circuit 25 as soon as the switch levers 62 and 66 are swung out of engagement with the contacts 61 and 65, respectively, due to the engagement of 110 the brush devices 13 and 14 with the sub-rails 3 and 4. Thus, the current furnished by the battery 29 will traverse the conductor 30, the solenoid 31, the conductor 32, the solenoid 33, the conductor 34, the switch 26 and conductor 28. Thus, the closed switch 26 serves to shunt off the switch levers 62 and 66 which have been opened, and this will prevent the solenoids 31 and 115 33 being deenergized by the opening of the switch levers 62 and 66, and in this manner, the valves 42 and 55 will remain closed in the absence of an accident to the system or the presence of a train upon the block C. The conditions above referred to will be 120 125 present also when the brush devices 13 and 14 pass over the sub-rails 5 and 6, in that the solenoids 31 and 33 will not be deenergized.

Supposing a train T' is occupying the 130

block C when the train T enters the block B, the train T' will bridge the partial track circuit by establishing a shunt across the rails 1 and 2, and cutting out the resistance 12 from the partial track circuit. Therefore, as soon as the brush devices 13 and 14 engage the sub-rails 3 and 4, they will close the circuit through the coöperating partial train and track circuits, but 10 since the resistance 12 has been cut out from the circuit, the current established by the battery 24 will be stronger, and will not only energize the magnet 19 sufficiently to attract the armature switch 26, but will also 15 sufficiently energize the magnets 18 and 20 so as to attract the armature switch 69. As a result, the current from the battery 29 will traverse the conductor 30, the solenoid 31, the conductor 71, the armature switch 69, 20 the conductor 72, and conductor 28. This will shunt out the solenoid 33, which will immediately become deenergized, and the spring 46' will then come into play for opening the valve 42. The valve 42 being opened 25 will admit the compressed air into the piston 37, and the piston 38 being actuated, will swing the throttle lever 40 partially back to initial position, and as a result the flow of steam to the engine cylinders will be 30 cut off partially, to reduce the speed of the train, and serve as a signal for warning the engineer of the impending danger, or that the train is entering a dangerous zone. Should the train proceed along the block B 35 to the other end thereof adjacent which the sub-rails 5 and 6 are located, without the engineer stopping the train, the train will be automatically brought to a halt. When the brush devices 13 and 14 move out 40 of engagement from the sub-rails 3 and 4, the train and track circuits will naturally be opened, and the electromagnets 17, 18, 19, 20 and 21 will be deenergized, and the current of the battery 29 will again traverse 45 the solenoid 33, but since the piston 38 of the cylinder 37 is not capable of swinging the throttle lever 40 open, the throttle lever will remain in the position to which it was 50 previously swung by the piston 38. Now, when the brush devices 13 and 14 engage the sub-rails 5 and 6, the partial train and track circuits will again coöperate to establish a 55 complete circuit through the conductor 16, the rail 5, the conductor 9, the rail 1, the train T', the rail 2, the conductor 11, and the rail 6. Thus, both of the resistances 8 and 12 are cut out, and this will still further increase the current flowing through the said circuit, and as a result, the least 60 sensitive magnets 17 and 21 will be energized sufficiently to attract the armature switch 73. This will cut out both of the solenoids 31 and 33 from the circuit 25, it being noted that the current from the battery 29 will flow through the conductor 75,

the switch 73, conductor 76, the conductor 64, and conductor 28. The solenoid 31 being deenergized will allow the valve 55 to swing open, which will permit the compressed air into the cylinder 47, and the piston 48 will therefore be actuated to swing the throttle lever 40 to initial position, and to thereby completely cut off the flow of steam to the engine cylinders. As soon as the piston 48 passes the end of the pipe 50, 70 the air will be admitted through the pipe 50 to the cylinder 51, and as a result, the piston 52 will be forced in the proper direction to actuate the brake valve 42, and as a result, the air brakes will be thrown into operation for bringing the train to a halt. 75

It will therefore be apparent that the present apparatus is operable to gradually reduce the speed of the train, as a caution, when it enters the block adjacent to a block 80 which is occupied by another train, and should the train entering the block continue to move into the dangerous zone, which creates an emergency or dangerous condition, the train will be automatically 85 stopped. The present apparatus is also operable for arresting the movement of the train, when any circuit is accidentally broken or opened, since this allows, directly or indirectly, the solenoids 31 and 33 to be 90 deenergized for opening the valves. A failure of the system to operate properly, therefore, will create an emergency or danger condition, resulting in the arresting or stopping of the train, until the danger is removed. 95

Fig. 2 illustrates a slight modification, in that the pipe 35 is not connected to a cylinder for operating the throttle valve, but on the other hand, the pipe 35 is provided beyond the valve 42 with a whistle or signal 77 which is adapted to be operated when the valve 42 is opened, and which will give a caution or warning signal to the engineer, when his train enters a block adjacent a 105 block already occupied, to enable the engineer to stop the train. 110

In Fig. 4, a modified form of brush device is illustrated, for coöperation with a modified form of sub-rail. This modified form of brush device 13' embodies a bell crank lever 66' fulcrumed to the frame 79' and having a conductor 16' of the partial train carried circuit connected thereto. The upstanding arm of the lever 66' carries an insulated contact 65' which is coöperable with a contact 65^a carried by the frame 79', the conductors 64' and 68' being connected to the respective contacts 65^a and 65'. A coiled wire retractile spring 81 connects the upstanding arm of the lever 66' and the frame 79', to return the lever 66' when it is released from the sub-rail, to thereby bring the contacts 65' and 65^a into engagement with one another. The sub-rails 3' 120

with which the outstanding or horizontal arm of the lever 66' is coöperable, is carried a suitable bracket 82 which has an overhanging portion from which the rail 3' depends, whereby the rail 3' will be protected from the elements and from objects dropped thereover. The outstanding arm of the lever 66' is adapted to pass under the rail 3', to thereby swing the lever 66' to the position illustrated in Fig. 4, and to separate the contacts 65' and 65".

It is of advantage to have the magnets 18 and 20 mounted upon the common core 22, and to have the magnets 17 and 21 mounted upon the common core 23, since should either one magnet of a pair become short circuited, the other magnet of the pair would still operate the coöperating armature switch.

Having thus described the invention, what is claimed as new is:—

1. In a train control system, the combination with a partial track circuit including in series, insulated traffic rails, a resistance therebetween, and a sub-rail connected to one of the traffic rails; of a normally closed train carried circuit including a source of electrical energy, an electrically operated device adapted to hold a train stopping mechanism in inoperative position, and a normally closed and a normally opened switch connected in parallel to one another; and a train carried partial circuit coöperating with the partial track circuit and including a contact shoe at one end engageable with the sub-rail, an electrical device for closing the aforesaid normally open switch, and an electrical device connected to the aforesaid train carried partial circuit for shunting out the first mentioned electrically operated device when said resistance is cut out to release the train stopping mechanism; the normally closed switch being operatively connected to the contact shoe whereby when the contact shoe engages the sub-rail the normally closed switch will be opened; and means for electrically connecting the other end of the train carried partial circuit and the other traffic rail.
2. In a train control system, the combination with a partial track circuit including in series, insulated traffic rails, a resistance therebetween, a pair of sub-rails one of which is connected to one traffic rail, and a resistance between the sub-rails; of a normally closed train carried circuit including a source of electrical energy, a pair of electrically operated devices, one of which is adapted to hold a train stopping mechanism in inoperative position, and a normally open and a normally closed switch connected in parallel to one another; and a train carried partial circuit coöperating with the partial track circuit and including a contact shoe at one end engageable with the sub-rails, an electrical device for closing said normally open switch, an electrical device connected to the normally closed train carried circuit for shunting out the second electrically operated device of the normally closed train carried circuit, and an electrical device connected to the normally closed train carried circuit for shunting out the first mentioned electrically operated device of the normally closed circuit, the said electrical devices of the train carried partial circuit being of different resistances, whereby the second mentioned electrical device of the train carried partial circuit will be operated when the first mentioned resistance is cut out and the third mentioned electrical device of the

sub-rails, an electrical device for closing the aforesaid normally open switch, and a pair of electrical devices connected to the aforesaid train carried partial circuit, said pair of electrical devices of the train carried partial circuit being less sensitive than the aforesaid electrical device of the train carried partial circuit and being connected to the aforesaid normally closed train carried circuit, the last mentioned pair of electrical devices being adapted to shunt out one or the other of the electrically operated devices of the normally closed train carried circuit, one of the said pair of electrical devices of the train carried partial circuit being less sensitive than the other and being adapted to operate when both resistances are cut out for shunting said electrically operated device of the normally closed circuit which holds the train stopping mechanism in inoperative position, the normally closed switch being operatively connected to the contact shoe whereby the contact shoe in engaging the sub-rail will open the normally closed switch; and means for electrically connecting the other end of the train carried partial circuit and the other traffic rail.

3. In a train control system, the combination with a partial track circuit including in series, insulated traffic rails, a resistance therebetween, two pairs of sub-rails, the sub-rails of one pair being connected to the traffic rails, and a resistance between a sub-rail of one pair and a sub-rail of the other pair; of a normally closed train carried circuit including a source of electrical energy, an electrically operated device adapted to hold a train stopping mechanism in inoperative position, a second electrically operated device, a normally open switch, and a pair of normally closed switches, the normally closed switches being arranged in parallel to the normally open switch; and a train carried partial circuit coöperating with the partial track circuit and including a pair of contact shoes engageable with the sub-rails of the respective pairs to close the circuit through the said partial circuits, an electrical device for closing said normally open switch, an electrical device connected to the normally closed train carried circuit for shunting out the second electrically operated device of the normally closed train carried circuit, and an electrical device connected to the normally closed train carried circuit for shunting out the first mentioned electrically operated device of the normally closed circuit, the said electrical devices of the train carried partial circuit being of different resistances, whereby the second mentioned electrical device of the train carried partial circuit will be operated when the first mentioned resistance is cut out and the third mentioned electrical device of the
